US00D940684S

(12) **United States Design Patent** (10) **Patent No.:** **US D940,684 S**
(45) **Date of Patent:** **** Jan. 11, 2022**

(54) **EARPHONES**

(71) Applicant: **Buddy Snow**, Medina, MN (US)

(72) Inventor: **Buddy Snow**, Medina, MN (US)

(**) Term: **15 Years**

(21) Appl. No.: **29/706,448**

(22) Filed: **Sep. 20, 2019**

Related U.S. Application Data

(63) Continuation-in-part of application No. 29/684,785, filed on Mar. 24, 2019.

(51) **LOC (13) Cl.** **14-01**

(52) **U.S. Cl.**

USPC **D14/205**; D14/223

(58) **Field of Classification Search**

USPC ... D14/205, 188, 192, 217, 372, 224.1, 639, D14/496, 432, 371, 125, 126, 129, 223; 2/171, 181, 209.13; 381/380, 381, 376, 381/312, 315, 322; 345/8; D24/190, D24/214; 601/57, 66, 46; 128/907; D6/601; 4/575.1

(57)

CLAIM

The ornamental design for earphones, as shown and described.

DESCRIPTION

FIG. 1 is a perspective view of earphones showing my new design;

FIG. 2 is a front view thereof;

FIG. 3 is a rear view of earphones thereof;

FIG. 4 is a right side elevation view of earphones showing my new design;

FIG. 5 is a left side view of the earphones;

FIG. 6 is a top view thereof; and,

FIG. 7 is a bottom view thereof.

The broken lines depict environment that forms no part of the claimed design.

1 Claim, 7 Drawing Sheets
